W. J. HINES

VANITY CASE

Filed March 17, 1926

INVENTOR
William J. Hines.
by
Arthur B. Rankin,
ATTORNEY

UNITED STATES PATENT OFFICE.

WILLIAM J. HINES, OF HARTFORD, CONNECTICUT, ASSIGNOR TO THE FULLER BRUSH COMPANY, OF HARTFORD, CONNECTICUT, A CORPORATION OF CONNECTICUT.

VANITY CASE.

Application filed March 17, 1926. Serial No. 95,287.

My invention relates to that class of toilet articles for holding face powder and the like, more especially for application uses, and an object of my invention, among others, 5 is the provision of a device of this class wherein the material in a powdered state may be contained, together with a pad for applying the material and for retaining such material in the compartment designed for it; 10 and a further object of this invention is to provide a device that shall be convenient for use, that may be sightly, and that may be produced at a minimum expense.

One form of device embodying my invention and in the construction and use of which the objects herein set out, as well as others, may be attained, is illustrated in the accompanying drawings, in which—

Figure 1 is a top view of a vanity case 20 embodying my invention.

Figure 2 is a view in side elevation of the same.

Figure 3 is a view similar to Figure 1, but with the cover open.

25 Figure 4 is a view in section on a plane denoted by the dotted line 4—4 of Figure 1.

Figure 5 is a bottom view of the device.

In the accompanying drawings the numeral 6 denotes the body or box portion of 30 the case that may be constructed of any suitable material and of any desired form, preferably of generally round form when viewed from the top, but with that edge containing the hinge cut off to form a straight edge 7, 35 the hinge 8 at this straight edge pivotally attaching the cover 9 to the box or body portion. This cover may contain a mirror 10 secured in place by a cleat 11 forming a border extending entirely around the mirror 40 and secured to the cover in any suitable manner. The cover, the box and said cleat are all of horseshoe shape.

A powder chamber 12 is formed within a case 13, preferably round when viewed from 45 the top and having a peripheral flange 14 by means of which it is secured to the bottom of a tray 15 fitted within the box. The top of the case 13 is depressed, as at 16, and this depressed portion is provided with an opening 17 into the chamber 12. This chamber 50 is spaced from the wall of the box all around to form a catch pocket within which any powder escaping from within the chamber

will be caught and thereby prevented from sifting out underneath the cover. 55

A puff 18 is formed of a size to fit the depression 16 and close the opening 17, this puff being of a thickness a little greater than the distance between the bottom of the depression 16 and the mirror 10 so that when 60 the cover 9 is closed the puff will be pressed into contact with the bottom of the depression 16 and securely seal the opening 17, the soft application face of the puff being applied in the depression 16. 65

The bottom of the box is depressed to form a cavity 19 with a mouth 20 at the back end thereof. The tray 15 is separately formed from the box and when the tray is in place the bottom of the tray forms one wall 70 of the cavity 19, and as shown in Figure 4 of the drawings. Holes 21 are formed through the back edge within which clips 22 overturned from one of the hinge members may be received, said overturned clip being 75 for the purpose of securing the hinge member in place. The wall of the tray will have sufficient flexibility to enable it to be sprung over the clips and then resume its natural form with the clips in place in said holes 80 whereby the tray will be retained in place.

A spring latch 23 is secured to the inner wall of the tray 15, this latch having a tray retaining lip 24 extending through a hole in the front wall of the tray and a retaining 85 hole 25 in the front of the box. Said latch also has a cover retaining lip 26, the latter extending over the top edge of the tray and into a hole 27 in the front edge of the cover. The cavity 19 is intended as a receptacle for a comb 28 or other article as may be desired. 90

In accordance with the provisions of the patent statutes I have described herein the principles of operation of my invention, together with the device which I now consider to represent the best embodiment thereof; but I desire to have it understood that the device shown is only illustrative and that the invention may be carried out by other 100 means and applied to uses other than those above set out.

I claim—

1. A vanity box including a case rigidly secured to the bottom of and rising within the 105 box to form a powder chamber and spaced

from the wall of the box all around from the top downward to form a catch pocket for powder, said case having an opening at the top, a powder puff to close said opening, and a cover to secure said puff in place.

2. A vanity box including a case having a flanged edge secured within the box at the bottom thereof, said case rising from the flanged edge to form a powder chamber having an opening at the top, a powder puff to close said opening, and a cover to secure said puff in place.

3. A vanity box including a tray separately formed and secured within the box, a case rising from the bottom of the tray forming a powder chamber spaced from the wall of the tray all around to form a catch pocket for powder, said case having an opening at its top, a powder puff, and a

cover to press said puff into place to close 20 said opening.

4. A vanity box including a tray removably located within the box, a flat spring arm secured at one end to the inner surface of said tray and having a catch lip at the 25 opposite end adapted to pass through an opening in the tray and box to hold the tray in place.

5. A vanity box including a tray removably secured within the box, a cover hinged 30 to the box, a flat spring arm secured at one end inside of the tray and having two catch lips at its opposite end, one to engage openings to hold the tray in place and the other to engage the cover to retain it in its closed 35 position.

WILLIAM J. HINES.
